(57) **CLAIM**

The ornamental design for a case for electronic communications device, as shown and described.

DESCRIPTION

FIG. 1 is a top, rear, left-side perspective view showing a first embodiment of a case for electronic communications device embodying my new design;

FIG. 2 is a rear view thereof;
FIG. 3 is a front view thereof;
FIG. 4 is a left-side view thereof;
FIG. 5 is a right-side view thereof;
FIG. 6 is a top view thereof;
FIG. 7 is a bottom view thereof.
FIG. 8 is a partially enlarged front view thereof, taken from FIG. 3;
FIG. 9 is a top, rear, left-side perspective view showing a second embodiment of a case for electronic communications device embodying my new design;
FIG. 10 is a rear view thereof;
FIG. 11 is a front view thereof;
FIG. 12 is a left-side view thereof;
FIG. 13 is a right-side view thereof;
FIG. 14 is a top view thereof;
FIG. 15 is a bottom view thereof;
FIG. 16 a partially enlarged front view thereof, taken from FIG. 11;
FIG. 17 is a top, rear, left-side perspective view showing a third embodiment of a case for electronic communications device embodying my new design;
FIG. 18 is a rear view thereof;
FIG. 19 is a front view thereof;
FIG. 20 is a left-side view thereof;
FIG. 21 is a right-side view thereof;
FIG. 22 is a top view thereof;
FIG. 23 is a bottom view thereof;
FIG. 24 is a partially enlarged front view thereof, taken from FIG. 19;
FIG. 25 is a top, rear, left-side perspective view showing a fourth embodiment of a case for electronic communications device embodying my new design;
FIG. 26 is a rear view thereof;
FIG. 27 is a front view thereof;
FIG. 28 is a left-side view thereof;
FIG. 29 is a right-side view thereof;
FIG. 30 is a top view thereof;
FIG. 31 is a bottom view thereof; and,
FIG. 32 is a partially enlarged front view thereof, taken from FIG. 27.

The dash-dash broken lines in FIGS. 1, 2, 17, and 18 represent unclaimed portions of the case for electronic communications device.

(Continued)

The heavy black lines in FIGS. 3, 11, 19, and 27 and the dot-dot-dash broken lines in FIGS. 8, 16, 24, and 32 are included for the purpose of illustrating the partially enlarged views and form no part of the claimed design.
